INTERNAL-COMBUSTION ENGINE

William H. McInturff, Warrington, Fla.

Application July 20, 1942, Serial No. 451,655

2 Claims. (Cl. 74—40)

(Granted under the act of March 3, 1883, as
amended April 30, 1928; 370 O. G. 757)

1

The invention described herein may be manufactured and used by or for the Government for governmental purposes, without payment to me of any royalty thereon.

This invention relates to internal combustion engines, and the primary object thereof is to provide an internal combustion engine of such construction that a minimum amount of fuel is consumed in obtaining the maximum amount of power therefrom.

Another object of the invention is to provide means in connection with an internal combustion engine whereby the pistons are given a plurality of working and compression strokes in the cylinders for each revolution of the crankshaft, thus producing more power on a lesser number of pistons and cylinders and resulting in the reduction of the amount of fuel consumed by the engine.

Another object of the invention is to provide means for connecting the pistons of a multi-cylinder internal combustion engine to a single crank on the crank shaft thereof in such a manner as to impart a continuous rotary motion to the shaft and to provide means for actuating the respective intake valves of the cylinders by a single cam mounted on the main shaft and the respective exhaust valves of the cylinders by a single cam also mounted on said crankshaft thereby eliminating the necessity of employing chains, sprockets, gears and other such elements in actuating said valves.

Another object of the invention is to provide means in connection with an internal combustion engine that a leverage on the pistons is provided whereby an economy in power is effected in compressing the charge.

Another object of the invention is to provide connecting means between a crankshaft and the reciprocating pistons of an internal combustion engine which will eliminate side thrust of the pistons in the cylinders and will reduce the commonly called slap and push of the pistons to a minimum.

Another object of the invention is to provide connecting means including a driving rod between a single crank on the crankshaft and piston rods for the pistons of a multi-cylinder engine whereby the pistons are run in the cylinders at double the speed of the crankshaft, thereby insuring more steady power, also giving an impulse at the upper and lower operative positions of the single crank on the crankshaft which tends to balance the torque for producing a more equal distribution of vibrations and eliminating

2

the necessity of using the conventional camshaft on the engine.

Heretofore the pistons on internal combustion engines were caused to have only one working and compression stroke for each revolution of the crankshaft, resulting in the use of the maximum amount of fuel in running the engine.

It is therefore the aim and purpose of this invention to provide connecting means between the crankshaft of an internal combustion engine and the pistons for producing a plurality of working and compression strokes in the cylinders for each revolution of the crankshaft, thus providing more power on a lesser number of pistons and cylinders resulting in a great saving of fuel for running the engine.

With the above and other objects and advantages in view, the invention consists of certain features of construction and arrangement of the several parts to be hereinafter fully described and illustrated in the accompanying drawings in which—

Fig. 1 is a transverse sectional elevation of the improved multi-cylinder internal combustion engine;

Fig. 2 is a longitudinal sectional elevation thereof taken on the line 2—2 of Fig. 1;

Fig. 3 is a diagrammatic representation of the single crank on the crankshaft being at the top dead center and illustrating the elements comprising the invention shown in operative positions for causing one of the pistons to have a suction stroke in a cylinder while another of the pistons has an expansion or power stroke in another cylinder;

Fig. 4 is a diagrammatic representation of the crank on the crankshaft actuated 90°, with the elements shown in operative positions for causing the pistons to have a compression and an exhaust stroke respectively;

Fig. 5 is a diagrammatic representation of the crank actuated 180° with the elements shown in operative positions for causing the pistons to have a power and suction stroke respectively;

Fig. 6 is a diagrammatic representation of the crank actuated 270° with the elements shown in operative positions for causing the pistons to have an exhaust and compression stroke respectively;

Fig. 7 is a horizontal sectional view taken on the line 7—7 of Fig. 1.

Referring more specifically to the drawings, the improved internal combustion engine indicated generally by A comprises a crankshaft 1 supported on bearings 2 on the upper ends of standards 3

which are suitably mounted on the base 4 of the crank case or housing 5 of the engine. One end of the crankshaft 1 is supported in a bearing 6 and extends through one side of the crank case 5 for supporting a fly wheel 7. A single crank 8 having counterweights 9 thereon is provided on the crankshaft 1 intermediate its ends. The lower end of a driving rod 10 is pivotally connected to the single crank 8 while its upper end is pivotally connected to a guide element 11 in the form of a block member which is slidably mounted in a vertically extending guideway 12, said guide element 11 being in turn pivotally coupled to one end of one of each of a pair of rods or links 13 and 13' of a toggle mechanism. The other ends of the links 13 and 13' are pivotally connected at 14 to the inner upper ends of a pair of bell cranks or angle levers 15 and 15' respectively, one of each of which bell cranks is mounted on opposite sides of the driving rod 10 and guideway 12. The bell cranks 15 and 15' are pivotally mounted at 16 and 16' to rock on a pair of brackets 17 and 17' respectively, suitably mounted on a supporting frame 18 positioned within a casing 19 on the upper end of which the cylinder blocks 20 and 20' are mounted. The cylinder 21 of the cylinder block 20 is provided with a suitable piston 22 that is adapted to reciprocate therein, which piston 22 is connected to one end of the piston rod 23, the opposite end of said piston rod 23 being pivotally connected at 24 to the outer end of the bell crank 15. The cylinder 21' of the cylinder block 20' is provided with a piston 22' having one end of the piston rod 23' connected thereto, with the other end of said rod 23' being pivotally connected at 24' to the outer lower end of the bell crank 15'.

The cylinder block 20 is provided with a water jacket 25 for cooling the cylinder 21 and has a cylinder head 26 containing an intake valve chamber 27 and an exhaust valve chamber 28 therein, and the cylinder block 20' is also provided with a water jacket 25' for cooling the cylinder 21' and has a cylinder head 26' containing an intake valve chamber 27' and an exhaust valve chamber 28' therein. The intake valve chamber 27 of the cylinder head 26 is connected in communication with the upper end of the cylinder 21 through an open port 29 and through an intake valve 30 seated therein, with the intake port 31 of the engine connected to any suitable source of fuel supply (not shown) for supplying charges of fuel to the cylinder 21, and the exhaust valve chamber 28 is connected in communication with the upper end of the cylinder 21 through an open port 32 and through an exhaust valve 33 seated therein with an exhaust port 34 of the engine.

The intake valve chamber 27' of the cylinder head 26' on the cylinder block 20' is connected in communication with the upper end of the cylinder 21' through an open port 29' and through an intake valve 30' seated therein with the intake port 31' connected to any suitable source of fuel supply (not shown) for supplying charges of fuel to the cylinder 21', and the exhaust valve chamber 28' is connected in communication with the upper end of the cylinder 21' through an open port 32' and through an exhaust valve 33' seated therein with an exhaust port 34' of the engine. Separate means in the form of spark plugs 35 and 35', in connection with a suitable ignition device (not shown) for igniting the explosive charge in the cylinders 21 and 21' of the cylinder blocks 20 and 20', respectively, are provided. The intake and exhaust valves 30 and 33, respectively, of the

cylinder block 20 and the intake and exhaust valves 30' and 33', respectively, of the cylinder block 20' are of the usual construction employed in engines of this kind, with the intake valves 30 and 30' being disposed on one side of the cylinders 21 and 21' respectively, and the exhaust valves 33 and 33' being disposed at the opposite side of the cylinders.

The intake valves 30 and 30' for the cylinders 21 and 21', respectively, are operated by means in the form of a pair of levers 36 and 36', pivoted together by a pin 37 mounted on a bracket 38 suitably secured to the lower surface of the frame 18. The pair of levers 36 and 36' comprises arms 39 and 39' and legs 40 and 40' which arms 39 and 39' extend in diametrically opposite directions from each other from the pivot pin 37 and bear at their outer ends against the lower ends of the rods 41 and 41' that operate the intake valves 30 and 30', respectively, against the action of the springs 42, and the legs 40 and 40' extend downwardly from the pivot pin 37, with the lower free ends 43 and 43' of the legs being bent and extending in opposed relation to each other for engaging with a single cam 44 fixedly mounted on the crankshaft 1 adjacent to one side of the single crank 8.

The exhaust valves 33 and 33' of the cylinders 21 and 21', respectively, are similarly operated by means in the form of a pair of levers 45 and 45' pivoted together by a pin 37' mounted on a bracket 38' suitably secured to the lower surface of the frame 18. The pairs of levers 45 and 45' comprises arms 46 and 46' and legs 47 and 47', which arms 46 and 46' extend substantially horizontally outwardly from the pin 37' in diametrically opposite directions from each other and bear at their outer ends against the lower ends of the rods 48 and 48' that operate the exhaust valves 33 and 33', respectively, against the action of the springs 42', and the legs 47 and 47' extend downwardly from the pivot pin 37' with the lower free ends 49 and 49' of the legs being bent and extending in opposed relation to each other for engaging with a single cam 44' fixedly mounted on the crankshaft 1 adjacent to the other side of the single crank 8 on the crankshaft 1. The cam 44 has a lobe 50 thereon which extends outwardly therefrom substantially 90° from the lobe 50' on the cam 44' for a purpose which will hereinafter appear.

In the operation of the improved internal combustion engine, assuming that the elements comprising the invention are in the operative positions as indicated in Figs. 1, 2 and 3, with the crank shaft 1 driven in a clockwise direction as indicated by the arrow, and that the lobe 50 on the cam 44 for actuating the pairs of levers 36 and 36' which actuate the intake valves 30 and 30' on the cylinder blocks 20 and 20', respectively, has been engaged by the lower end 43 on the leg 40 of the lever 36 whereby the lever is rocked on its pivot 37, forcing the arm 39 upwardly and unseating the intake valve 30 through the rod 41 against the action of the spring 42, thereby permitting a charge of fuel to enter the intake chamber 27 of the cylinder head 26 through the intake port 31 and to enter the cylinder 21 through the open port 29, and with the lobe 50' on the cam 44' for actuating the pair of levers 45 and 45' which actuate the exhaust valves 33 and 33', respectively, being moved out of engagement with the lower ends 49 and 49' on the legs 47 and 47' thereof, whereby the exhaust valves 33 and 33' of the cylinder blocks 20 and 20', re-

spectively, are held by their springs 42' in a seated position on their respective exhaust ports 34 and 34'. Also assuming that a charge of fuel has entered the cylinder 21' of the cylinder block 20' and has been ignited by the spark plug 35', whereby the piston 22' is caused to have a power stroke forcing the piston 22' downwardly in the cylinder, thus pushing the piston 23' against the outer lower end of the bell crank 15' and rocking the bell crank outwardly on its pivot 16', which causes the inner upper end of the bell crank 15' to be moved outwardly, pulling on the link 13' pivoted to a guide element 11, and moving the guide element downwardly in the guideway 12 whereby the driving rod 10 is pulled downwardly, rotating the single crank 8 which in turn rotates the crank shaft 1. The inner end of the link 13 also pivoted to the guide element 11 is pulled downwardly which causes the outer end of the link 13 to push outwardly on the inner upper end of the bell crank 15, thereby rocking the bell crank 15 outwardly on its pivot 16 which causes the outer lower end of the bell crank to be moved downwardly, thus pulling downwardly on the piston rod 23 and giving the piston 22 in the cylinder 21 an intake or suction stroke.

As the crankshaft 1 is rotated, the lobe 50 on the cam 44 is gradually moved out of engagement with the lower end 43 on the leg 40 of the lever 36, thus causing the lever 36 to rock on its pivot 37 and moving the outer end of the arm 39 of the lever downwardly, permitting the spring 42 to pull downwardly on the intake valve 30 for seating it on the intake port 31. The lobe 50' on the cam 44' for operating the pair of levers 45 and 45' which operate the exhaust valves 33 and 33', respectively, is then caused to gradually engage the lower end 49' on the leg 47' of the lever 45', whereby the lever 45' is rocked on its pivot 37', moving the outer end of the arm 46' upwardly which pushes up on the rod 48' to unseat the exhaust valve 33' from the exhaust port 34' as illustrated in Fig. 4.

Upon the single crank 8 having been rotated 90°, the pistons 22 and 22' will have completed their downward stroke, with the links 13 and 13' of the toggle mechanism being in a straight line, whereby the piston 22 is in a position to have a compression stroke and the piston 22' is in a position to have an exhaust stroke as illustrated in Fig. 4. As the single crank 8 is further rotated the driving rod 10 will still further be pulled downwardly, pulling on the guide element 11 which causes the guide element to move downwardly in the guideway 12 and pulling downwardly on the inner ends of the links 13 and 13' pivoted to the guide element, whereby the outer ends of the links are caused to pull inwardly on the inner upper ends of the bell cranks 15 and 15' for rocking the bell cranks inwardly toward each other on their pivots 16 and 16', respectively. As the inner upper ends of the bell cranks are pulled inwardly, the outer ends thereof are caused to move upwardly, thereby causing the piston 22 to be given a compression stroke and the piston 22' to be given an exhaust stroke as illustrated in Fig. 4. The lobe 50 is then gradually moved from engagement with the lower end 49' on the leg 47' of the lever 45', and the spring 42' returns the exhaust valve 33' to its seated position on the exhaust port 34', pushing down on the piston rod 48' which in turn pushes down on the outer end of the arm 46' of the lever 45' and causes the lower end 49' of the leg 47' of the lever to engage with the circular portion of the cam 44'. Upon

the continual rotation of the single crank 8, the lobe 50' on the cam 44' is caused to gradually engage the lower end 43' on the leg 40' of the lever 36' which actuates the lever to raise the intake valve 30' whereby a charge of fuel is caused to enter the intake chamber 27' of the cylinder head 26' of the cylinder block 20' through the intake port 31' and to enter the upper end of the cylinder 22' through the open port 29'.

Upon the crank 8 being rotated 180°, the pistons 22 and 22' will have completed their compression and exhaust strokes and the charge of fuel in the cylinder 21 will be ignited by the spark plug 35 which causes the piston 22 to have a power stroke, thereby pushing down on the outer end of the bell crank 15 and rocking the bell crank outwardly on its pivot 16, pulling outwardly and downwardly on the outer end of the link 13. Upon the link 13 being pulled outwardly and downwardly, the inner end thereof, pivoted to the guide element 11, causes the guide element to pull upwardly on the drive rod 10 to rotate the single crank 8. The upward movement of the guide element rocks the bell crank 15' on the pivot 16' through the link 13' whereby the piston 22' is caused to have a suction stroke as illustrated in Fig. 5.

Upon the continual rotation of the crankshaft 1, the lobe 50' on the cam 44' gradually engages with the lower end 49 on the leg 47 of the lever 45 for opening the exhaust valve 33, whereupon the products of combustion may leave the exhaust port 34. After the crank 8 has been rotated 270°, the pistons 22 and 22' will have completed their power and suction stroke and, upon further rotation of the crankshaft 1, the piston 22 is given an exhaust stroke and the piston 22' is given a compression stroke as illustrated in Fig. 6.

By this construction, the driving rod 10 is the connecting link which transmits the power from the pistons 22 and 22' to the crankshaft 1. The pistons 22 and 22' will run double the speed of the crankshaft, insuring more steady power, also giving an impulse at the top and bottom operative positions of the crank 8, which has a tendency to balance the torque and to give a more equal distribution of vibrations. The leverage of the bell cranks 15 and 15', in conjunction with the speed of the pistons transmitted through the links 13 and 13' of the toggle mechanism and driving rod 10 to the crankshaft 1, will produce more steady power on a lesser number of cylinders. The commonly called slap and push in this engine design occurs on the slide block 11 but when power is applied to the load, the pull of the links 13 and 13' is in the opposite direction of the slap and push whichever the case may be, hence, the slap and push will be at a minimum. Through the medium of the pairs of levers, one cam operates both exhaust valves; likewise, the other cam operates both intake valves. So instead of having one cam for each valve in this case, one cam operates two valves for different cylinders.

It will thus be seen that there is herein provided a novel and efficient form of internal combustion engine which is well adapted for all of the purposes indicated. Even though there has herein been shown and described an engine comprising two cylinders in which an explosion takes place above the pistons in one of each of the cylinders when the single crank on the crankshaft is at its bottom and top operative positions on each cycle of operation, which is equivalent to using four cylinders and pistons of the present day motor, it is nevertheless to be understood that

six cylinders with three cranks at 120° apart with an impulse given thereto every 60° , which is equivalent to twelve cylinders and pistons of the present-day motor may be used, or ten cylinders and pistons with five cranks at 72° apart may be employed with an impulse given thereto every 36° which is equivalent to a potential twenty cylinder engine. Also fourteen cylinders and pistons with seven cranks at $51\frac{1}{7}^\circ$, with an impulse given thereto every $25\frac{5}{7}^\circ$, which is equivalent to a potential twenty-eight cylinder engine may be employed without departing from the spirit or scope of the invention.

Having described my invention, what I claim as new and wished to secure by Letters Patent is:

1. A pair of members operable in a prearranged order, a rotary member, and means connected to be actuated by said pair of members and connected to drive said rotary member, said means including a driving rod connected to said rotary

member, a pair of pivotally mounted bell crank levers operable in opposed and unopposed relation, links connecting said levers with said driving rod, and rods connecting said levers with said pair of members.

2. A pair of members operable in a prearranged order, a rotary member including a crank, and means connected to be actuated by said pair of members and connected to drive said rotary member, said means including a driving rod connected to said crank, a pair of pivotally mounted bell crank levers operable in opposed and unopposed relation, links, one of each of said links connecting one end of each of said bell crank levers with said driving rod, and rods, one of each of said rods connecting one of each of the other ends of said levers with one of each of said pair of members.

WILLIAM H. MCINTURFF.
